MERRY-GO-ROUND FOR CHILDREN

Milton G. McKee, Youngstown, Ohio

Application June 29, 1950, Serial No. 10,838

Term of patent 3½ years

(Cl. D34—5)

To all whom it may concern:

Be it known that I, Milton G. McKee, a citizen of the United States, residing at Youngstown, in the county of Mahoning and State of Ohio, have invented a new, original, and ornamental Design for a Merry-Go-Round for Children, of which the following is a specification, reference being had to the accompanying drawing forming part thereof.

Figure 1 is a perspective view of a merry-go-round for children, showing my new design, and

Figure 2 is a perspective view illustrating the design as viewed substantially from the rear of

Figure 1, this figure being drawn to a slightly larger scale.

I claim:

The ornamental design for a merry-go-round for children, substantially as shown.

MILTON G. MCKEE.
